(57) **CLAIM**

The ornamental design for a sound bar, as shown and described.

DESCRIPTION

FIG. 1 is a first perspective view of a sound bar showing my new design;

FIG. 2 is a second perspective view thereof;

FIG. 3 is a front view thereof;

FIG. 4 is a back view thereof;

FIG. 5 is a left side view thereof;

FIG. 6 is a right side view thereof;

FIG. 7 is a top view thereof;

FIG. 8 is a bottom view thereof;

FIG. 9 is a partially enlarged view thereof, taken from FIG. 1; and,

FIG. 10 is another partially enlarged view thereof, taken from FIG. 1.

The dot-dash broken lines of FIGS. 1, 9, 10 are included to show partially enlarged views only and form no part of the claimed design.
